George W. Porter, Inventor

C. Snow & Co.

UNITED STATES PATENT OFFICE.

GEORGE W. PORTER, OF MUSCATINE, IOWA.

PRINTING-PRESS.

SPECIFICATION forming part of Letters Patent No. 640,808, dated January 9, 1900.

Application filed May 17, 1899. Serial No. 717,201. (No model.)

To all whom it may concern:

Be it known that I, GEORGE W. PORTER, a citizen of the United States, residing at Muscatine, in the county of Muscatine and State 5 of Iowa, have invented a new and useful Printing-Press, of which the following is a specification.

My invention relates to printing-presses especially designed for taking proof-impressions from job, news, and book type-forms in galleys or locked forms, although it may be used for printing purposes generally; and the primary object in view is to provide a simple construction in which the parts are 15 arranged to enable proofs to be obtained with ease and celerity.

A further object is to provide a platen-operating mechanism, which includes a powerful leverage appliance arranged to be easily 20 operated by the simple pull of a hand-lever by the pressman, and with this leverage appliance is associated a device for regulating the pressure exerted by the platen upon the blanket and type-form.

With these ends in view the invention consists in the novel combination of elements and in the construction and arrangement of parts, as will be hereinafter fully described and claimed.

To enable others to understand the invention, I have illustrated a preferred embodiment thereof in the accompanying drawings, forming a part of this specification, and in which—

Figure 1 is a perspective view of a printing-press constructed in accordance with my invention. Fig. 2 is a vertical sectional elevation taken longitudinally through the press. Fig. 3 is an enlarged detail view of 40 the knuckle-lever devices for exerting pressure upon the platen. Fig. 4 is a detail view of the type-bed having the hinged frisket and removed from the press.

The same numerals of reference are used 45 to indicate like and corresponding parts in each of the several figures of the drawings.

The framework 10 of my improved printing-press is supported at a proper height above the floor by the legs 11, and projecting 50 upwardly from the sides of this frame are the standards 12. These standards are disposed parallel to each other at the middle of

the frame, and they are constructed to form the vertical slots or guideways 13. The upper ends of the standards are joined together 55 by a bridge-beam 14, which may be of any preferred construction, and which serves to strongly brace the standards 12 to which it is united.

The sides of the frame 10 are fashioned to 60 accommodate the horizontal steel guideways 15, which are fastened by bolts to the frame 10 and extend out over and are supported by brackets 16, making a continuous track for the horizontally-slidable type-bed. These 65 tracks, as well as the horizontal rail 17, are adjustable vertically by the use of set-screws 17^a, fastened to the frame under each end of guideways 15 and the rail 17. The frame 10 is furthermore provided with a horizontal 70 rail 17, which is suitably fixed to said frame and is arranged in a position between and parallel to the brackets 16, and the upper face of this middle rail 17 is provided with a longitudinal channel or groove 18. 75

19 designates the slidable type-bed, which has its edges fitted in the guideways 15 of the frame and is adapted to slide horizontally therein, and this type-bed is arranged to be withdrawn from the guideways of the frame 80 for the purpose of resting upon the brackets 16 and the rail 17, whereby said type-bed may be supported on the frame at one side of the path of the vertically-reciprocating platen. The type-bed when withdrawn from the path 85 of the platen rests upon the brackets 16, and to prevent said type-bed from having edgewise displacement on the brackets and with relation to the guideways 15 of the frame I employ a flange 20, which is fixed on the bottom 90 of the bed in a position to enter the groove 18 of the rail 17. This flange serves to position the type-bed for proper entrance to the guideways of the frame when adjusting the bed below the platen, and the rail 17 is thus 95 adapted to coact with the guideways 15 in directing the horizontal travel of the type-bed with relation to the path of the platen.

The platen 21 is arranged between the standards 12 to reciprocate vertically within 100 the press-frame, and said platen is provided with fast or integral guide-lugs 22, which are fitted snugly to the guideways 13 of the standards 12, so as to slide freely therein. The

platen is supported normally in a horizontal plane above the path of the type-bed and the frisket thereon by the action of strong coiled springs 23, which are fitted in the lower parts 5 of the slotted standards 12, so as to engage with the guide-lugs 22 of the platen. The lower ends of these lifting-springs are seated upon the bottoms of the guideways in the standards, while the upper ends of said springs 10 act against the guide-lugs 22 for the purpose of lifting the platen to a position above the frisket and blanket on the slideable type-bed, and said frisket is connected by hinge-joints with the type-bed, so as to travel therewith 15 and to be capable of adjustment relatively to the type-bed for the purpose of permitting ready access to be obtained to the bed for placing or removing the form. The preferred means which I employ for the attachment of 20 the frisket to the bed consists of hinge-plates 25, which are fastened to the frisket at two of the corners thereof, and these hinge-plates are connected by horizontal pintles 25^a to lugs 26, which are fast or integral with the 25 type-bed.

As is usual in the art, the type-bed should be equipped with means for clamping the columns of type or the type-form to the bed, and in connection with the bed and the frisket the usual blanket is employed, as will be 30 readily understood by those skilled in the art. The reciprocating platen 21 is or may be cast in a single piece of metal, and on its upper face said platen has a central thrust-block 35 27, in the upper face of which is a recess 28, forming a seat for one end of one member of a knuckle-lever mechanism adapted to exert pressure upon the platen.

The bridge-beam 14 of the press-frame is 40 provided at its middle with a guide-clip 29, which may be fixed to the bridge-beam in any suitable way, and to this guide-clip is slidably fitted the upper thrust-block 30, which is disposed in the same vertical plane 45 with the thrust-block 27, that is fast with the reciprocating platen. This upper thrust-block 30 is designed to be adjusted on the guide-clip and the bridge-beam with relation to one member of the knuckle-levers, and in 50 its lower face said upper thrust-block has a recess 31, forming a seat for the other member of the knuckle-lever mechanism. It will thus be seen that the platen is provided with a fast thrust-block, which is adapted to 55 partake of the vertical travel of said platen under the influence of the knuckle-lever mechanism, while the other thrust-block is mounted on the fixed part of the frame for adjustment relatively to the thrust-block on the platen. 60 This adjustable thrust-block is confined slidably in place for proper engagement with the guide-clip, and with the adjustable thrust-block is associated a vertical adjusting-screw 46, which works in a nut or threaded bearing 65 47, provided on the bridge-beam 14. This adjusting-screw has a swivel connection with the adjustable thrust-block in order to raise

and lower the latter and adapt it to slide on the guide-clip.

The knuckle-lever mechanism consists of 70 two members 32 33, which are fitted, respectively, to the seats of the thrust-blocks and are seated one against the other, and with the knuckle-levers is combined a hand-operated lever by which the knuckle-levers may be 75 brought into alignment substantially with each other for the purpose of imparting a quick travel to the platen and of exerting powerful pressure thereon by the simple pull of the hand-lever. The member 32 of the 80 knuckle-lever has one end thereof formed to provide an angular arm 34, which in turn is provided with a lateral offset 35, having the seat 36. The extremity of the lever-arm 32 is rounded at 37 to fit in the seat 31 of the 85 upper thrust-block 30, and the opposite end of this lever member 32 is provided with the longitudinal slot 38, in which is pivoted an arm of the hand-lever 41. The other member 33 of the knuckle-lever mechanism is a 90 straight bar having rounded ends 39, one of which is fitted in the seat 28 of the lower thrust-block, while the other end occupies the seat 36 near the offset end of the lever member 32. The lever member 33 is slotted 95 at 40 for a part of its length to enable the arm 41^a of the lever 41 to pass therethrough, and this arm 41^a enters the slot 38 of the lever member 32, thereby adapting the lever-arm to be pivoted at 41^b in the slotted end of 100 the lever member 32.

The operating-lever 41 is arranged to travel in a horizontal path by direct pull of the operator thereon, and at one end said lever is provided with a head 42, which is fitted between lugs 43 on a depending arm 44 of the bridge-beam 14, the lever-head being confined in place between the lugs by a vertical pivotal bolt 45. The arm 41^a is in the same vertical plane as the members of the toggle-joint, 110 and this arm is fitted loosely in a slot of the member 32. One end of the arm 41^a is attached to a sleeve, which is fitted loosely on the horizontal lever 41, so as to be free to slide and turn thereon, while the other end of the arm is pivoted in the slotted end of the toggle member 32 in a manner to turn freely 115 on a horizontal axis. It is thus seen that the opposite ends of the connecting-arm 41^a are connected loosely to the lever 41 and to the 120 toggle member 32, so as to compensate for the differences in the arcs of movement of the hand-lever and the toggle member 32, which, it is to be observed, move on the centers 42 and 37, respectively. 125

From the foregoing description it will be seen that the two-part knuckle-lever mechanism has one member seated against a thrust-block on the platen, the other member seated against the thrust-block which normally occupies a stationary position on the bridge-beam of the frame, and the two members bear one against the other, so that the members 33 may assume inclined positions to a vertical

line which intersects the axes of the seats in the two thrust-blocks, as clearly shown by full lines in Fig. 3. The seats between the thrust-blocks and the lever members, as well as the connection between the members, thus serve to retain the parts in their proper operative positions, and said seats also insure easy and free turning of the members with minimum friction and wear on the several parts. The hand-operating lever has its arm 41^a pivoted to one lever member, and fitted slidably through the slot in the other lever member, and it assists in retaining proper alinement of the two members forming the knuckle-lever between the frame and the reciprocating platen. The upper thrust-block is adapted to be raised and lowered on the guide-clip of the press-frame by manipulating the adjusting-screw, and the distance between the two thrust-blocks, which are carried, respectively, by the frame and the platen, may be varied in order to effect variations in pressure of the platen upon the blanket and type-form.

The operation may be described as follows: The type-bed is moved horizontally to rest upon the brackets and rail of the frame, and the springs lift the platen to a position above the horizontal plane of the frisket, which is pivoted to the type-bed. The elevation of the platen under the pressure of the springs makes the lever member 33 bear against the lever member 32 to throw the two members into the inclined positions, and draws the operating - lever 41 inwardly toward the knuckle-levers. The operator may now lift the frisket, and the columns of type may be placed on the bed, the form may then be inked, and paper placed thereon in the usual way, after which the frisket containing the blanket should be lowered. The bed with a type-form thereon may now be moved in a horizontal direction into the guideways of the frame, and the flange and rail between the bed and frame coact in directing the type-bed properly to the guides 15 of said frame. After the bed has been moved into position the operator moves the lever 41 to draw on the arm 41^a for operating the knuckle-levers to force the platen upon the bed against the action of the lifting-springs. The outward movement of the lever 41 draws the arm 41^a to move the knuckle-lever member 32 inwardly toward the other member 33, and the two lever members are thus brought in a measure into vertical alinement—that is to say, the member 33 is in a vertical position between the lower thrust-block and the angular arm of the lever member 32. After the impression has been taken from the type-form the operator moves the lever 41 inwardly to throw the knuckle-levers into disaligned positions, and the pressure-springs then react to move the platen upwardly. The type-bed and frisket may now be withdrawn and the paper removed, after which the operation may be repeated, as desired.

Changes in the form, proportion, size, and the minor details of construction within the scope of the appended claims may be resorted to without departing from the spirit or sacrificing any of the advantages of this invention. 70

Having thus described the invention, what I claim is—

1. In a printing-press, the combination with a press-frame the bridge-beam of which is 75 provided with a screw-threaded perforation, and a vertically - reciprocating platen, of a guide-clip fixed to said frame, a thrust-block 80 slidably confined on the guide-clip, a regulating-screw mounted in the screw-threaded perforation of said frame and connected with the thrust-block to raise or lower the latter, another thrust-block fast with the platen, and a knuckle-lever mechanism having the two members connected together and seated 85 respectively against the adjustable thrust-block and the thrust-block on the platen, substantially as described.

2. In a printing-press, the combination with a press-frame the bridge-beam of which is 90 provided with a depending arm, and a vertically-reciprocating platen, of thrust-blocks connected respectively to said frame and the platen and provided with seats in their opposing faces, a knuckle-lever mechanism comprising 95 a member having an angular arm and a seat, one end of said lever member being fitted to the thrust-block on the press-frame, and another member provided with a slot and having its respective ends fitted to the seat of the 100 first-named member and the thrust-block on the platen, a hand-lever turning on a vertical axis on the depending arm of the press-frame, and an arm passing loosely through the slotted member of the knuckle-lever and having 105 one end pivoted to the other member of said knuckle-lever and connected at its other end loosely to the hand-lever, substantially as described.

3. In a printing-press, the combination with 110 a press-frame and a reciprocating platen, of thrust-blocks connected respectively to said frame and platen, lever members which are seated respectively in said thrust-blocks and fitted operatively one to the other, one of said 115 lever members having a lateral offset and a seat therein, and the other lever member provided with a longitudinal slot and with a head to fit in said seat, a hand-lever fulcrumed on the frame to turn on a vertical axis, and an 120 arm connected loosely with the hand-lever, pivoted to one member of the knuckle-lever and passing loosely through the slot of the other member of the knuckle-lever, for the purpose described, substantially as set forth. 125

4. In a printing-press, the combination with a frame the standards of which are slotted longitudinally, of a vertically-reciprocating platen provided with guide-lugs to slide in the slotted sides of said frame, springs in the bottoms of said slots acting against said platen to normally lift the latter, lever mechanism 130

for depressing the platen, and a horizontally-slidable bed fitted to said frame, said lifting-springs tending to normally maintain the platen in a horizontal plane above the path of the bed, substantially as described.

5. In a printing-press, the combination with a frame provided with brackets, and a vertically-reciprocating platen, of rails adjustably secured to said brackets, a horizontally-slid-10 able bed on said rails, and a frisket adjustably connected to said bed and adapted to travel therewith below the platen, substan-tially as described.

6. In a printing-press, the combination with 15 a frame the front and rear walls of which are each provided with brackets, and a vertically-reciprocating platen therein, of rails on said brackets, each of which is provided with per-forated lugs, bolts through the lugs and the 20 brackets, a horizontally-slidable bed guided on said rails for movement below the platen, and a frisket hinged to the bed to lie upon

the same and adapted to travel with said bed below the platen, substantially as described.

7. In a printing-press, the combination of a 25 frame provided with guideways and with fixed brackets, a grooved rail fixed to the frame be-tween said guideways and parallel to said brackets, a horizontally-slidable bed seated upon the brackets and having a flange adapt-ed to travel in the grooved rail to direct the bed into the guideways of the frame, a re-ciprocating platen guided in said frame, 30 springs acting against said platen to normally sustain the same in a horizontal plane above 35 the path of the bed, and mechanism for de-pressing the platen, substantially as described.

In testimony that I claim the foregoing as my own I have hereto affixed my signature in the presence of two witnesses.

GEORGE W. PORTER.
